GEORGE BENNETT, OF PHILADELPHIA, PENNSYLVANIA, ASSIGNOR OF ONE-HALF TO
HERMAN W. SCHULZ, OF PHILADELPHIA, PENNSYLVANIA.

DRAFTING-PEN.

1,099,160.

Specification of Letters Patent.

Patented June 9, 1914.

Application filed March 26, 1913. Serial No. 756,873.

To all whom it may concern:

Be it known that I, GEORGE BENNETT, a citizen of the United States, residing in the city of Philadelphia, county of Philadelphia, 5 and State of Pennsylvania, have invented certain Improvements in Drafting-Pens, of which the following is a specification.

My invention is designed to provide, particularly in a ruling pen, simple and efficient 10 means for opening or spreading the pen points and closing them without disturbing the gage or distance apart at which they have been set.

In the accompanying drawings, Figure 1 is 15 an elevation of a pen embodying my invention; Fig. 2 is a longitudinal sectional view of the same; Fig. 3 is a view of the handle detached from the pen proper; Fig. 4 is a view of the pen proper detached from the 20 handle; Fig. 5 is an elevation of a second form of the invention; Fig. 6 is a longitudinal sectional view taken through the pen proper of Fig. 5; Fig. 7 is an elevation of a 25 third form of the invention; Fig. 8 is a longitudinal sectional view taken through the pen proper of Fig. 7; and Fig. 9 is a sectional view taken on the line 9—9 of Fig. 7.

As illustrated in Figs. 1 to 4 inclusive, 30 the pen comprises the hollow handle 1 having the channeled shank 2 provided with the latch or movable side 3 pivoted on the screw 4, the axial passage 5 through the handle communicating with the longitudinal 35 channel or socket 6, of squared cross section, in the shank. The pen proper comprises the squared shank 7 having the resilient legs or bifurcations 8 provided with the points 9. In the assembled instrument, the shank 7 40 is disposed in the channel 6, with which it conforms; a rod 10, extending through the passage 5, is screwed into the shank 7; the latch 3 closes the open side of the channel 6, and a screw 11 passes through the hole 12 in the latch and the slots 13 in the legs 45 into the threaded hole 14 of the channeled shank. A cap 15, fixed to the top of the rod 10 and telescoped on the reduced tubular part 1' of the handle, affords convenient 50 means for manually reciprocating the rod 10 and the pen proper fixed thereto.

In Fig. 1, the parts are in the position 55 which they occupy in use, the cap 15 having been drawn back and, with it, the rod 10 and the shank 7, together with the parts

fixed thereto. In this position, the legs are pressed together by the engagement therewith of the walls of the channeled shank 2, the part 3 thereof being provided with a cam 3' which engages and frictionally 60 clutches a cam 8' of the adjacent leg.

In Fig. 2, the parts are in the position which they occupy when the points are open or spread, as in cleaning. This relation of the parts results from applying pressure 65 upon the end of the cap 15, which is communicated through the rod 10 to the shank 7 so that these parts are moved forward until the complementary cam 3' is cleared by the cam 8', when the points 9 are spread 70 as a consequence of the resiliency of the legs 8 now released from the lateral pressure which closes them; the freedom of outward movement of the legs in this position, as well as their resiliency, being facilitated by 75 the reduction of the metal with the production of the concavities 8''. It will be understood that when the screw 11 has been adjusted to set the points 9 in the desired relation, the points can be opened for cleaning 80 and closed for use without changing the position of the screw 11 or the relation of the points when closed, thus avoiding the usual necessity for nice adjustment, after opening the points, to maintain regularity 85 in the width of lines.

In the form of the invention illustrated in Figs. 5 and 6, the handle 16 has a shank 17 provided with the channel or socket 18 and with a latch or movable side 19 hinged or pivoted on the pintle 20. The pen proper comprises the shank 21 having connected therewith the legs 22 and 22' and the points 23 and 23'. The shank 21 is adapted to reciprocate in the socket 18 in which it is held by 95 the screw 24, which passes through the latch 19 and the slots 25 of the legs into the threaded hole 26. The latch 19 is provided with a cam 27 which is adapted for engaging the cam surface 28 of the leg 22 100 to frictionally clutch and hold the pen proper in its inner and operative position. When it is desired to spread the points 23 and 23', they are pulled outwardly, the cam 28 being disengaged from the cam 27 and 105 the leg 22 permitted to spring outwardly, which is facilitated by the concavity 22''. When the legs 22 and 22' are pushed inwardly, they are brought together by their engagement with the wall of the shank 17 110

which moves the points 23 and 23' to the operative relation, this relation remaining the same after once setting the screw 24.

In the form of the invention illustrated in Figs. 7, 8 and 9, the handle 28 is provided with a channeled or split shank 29 having the legs 29' and 29''. The pen proper is provided with the shank 30 having thereon the legs 31 and 31' provided with the points 32. A small T-bolt 33, having a head 33' which engages a recess 33'' in the part 29', passes through the slots 34 in the legs 31 and 31', and has a nut 35 set in the desired position thereon for holding the parts 29' and 29'' in the relation required for setting the points 32 when the shank 30 and the legs are in their inner position in the shank 29. When the pen proper is drawn to its outer position with relation to the shank 29, the points 32 are separated by the resiliency of the part 31, and when the pen proper is thrust inwardly with respect to the shank 29 the points are brought together at their operative relation by the engagement of the parts 29' and 29'' with the parts 31' and 31, the part 29'' being provided with the cam surface 36 which coacts with the complementary cam surface on the adjacent leg 31 to maintain this relation.

Having described my invention, I claim:

1. A drafting instrument comprising a handle provided with a socket, in combination with a furcated device having a shank movable longitudinally in said socket and blades adjusted relatively to each other by the longitudinal movement of said shank in said socket, and means engaging said handle for effecting the adjustment of said blades relatively to each other in the normal writing position of said device in said socket.

2. A drafting instrument comprising a handle provided with a shank containing a socket, a slotted furcated device having a shank movable longitudinally in and guided by said socket, and means engaged by said shank first named and disposed in the slot of said device for limiting the longitudinal movement thereof.

3. A drafting instrument comprising a handle provided with a shank containing a socket, a furcated device having a shank movable longitudinally in said socket, and means comprising a cam by which said device and handle are fixed together and the legs of said furcated device are adjusted.

4. A drafting instrument comprising a handle having a shank containing a socket,

a device having a shank movable longitudinally in said socket and furcations connected with said shank, and a movable member engaged in said first shank and engaging one of said furcations for adjusting it relatively to the other of said furcations.

5. A drafting instrument comprising a handle provided with a socket, a device having a shank movable in said socket and legs connected with said shank, said device being provided with a slot, and a member connected with said handle and passing through said slot whereby the longitudinal movement of said device is limited.

6. A drafting instrument comprising a handle provided with a socket and a movable bearing, a device having a shank movable in said socket and a slotted leg engaging said bearing, and a member connected with said handle and passing through said slotted leg whereby said bearing is adjusted and the movement of said first named device is regulated.

7. A drafting instrument comprising a handle containing a longitudinal passage and provided with a shank containing a channel having an open side, said shank having a movable member adapted for closing said side, a device having pointed legs extending into said channel and having slots in said legs, a device passing through said slots and connected with said shank whereby said movable member is held in the desired relation to one of said legs, and a rod extending through said passage and connected to said first named device whereby said legs are reciprocated, said legs being adapted for separating automatically and being pressed together by drawing them into said channel.

8. A drafting instrument comprising a handle having a shank with a socket therein, said shank being provided with an adjustable cam, in combination with a device having a shank movable in said socket and legs on said last named shank extending into said socket, one of said legs being resilient and having a cam surface engaging said cam, and means for adjusting the position of said cam and regulating its bearing with relation to said cam surface.

In testimony whereof I have hereunto set my name this 25th day of March, 1913, in the presence of the subscribing witnesses.

GEORGE BENNETT.
